UNITED STATES PATENT OFFICE.

HARRY H. BRYANT, OF ALLEGHENY, AND JOHN B. MCGAW, OF PITTSBURG, PENNSYLVANIA, ASSIGNORS OF ONE-THIRD TO OLIVER A. MACVAY, OF PITTSBURG, PENNSYLVANIA.

TROLLEY.

SPECIFICATION forming part of Letters Patent No. 723,646, dated March 24, 1903.

Application filed November 26, 1902. Serial No. 132,884. (No model.)

To all whom it may concern:

Be it known that we, HARRY H. BRYANT, residing at Allegheny, and JOHN B. MCGAW, residing at Pittsburg, in the county of Allegheny and State of Pennsylvania, citizens of the United States of America, have invented certain new and useful Improvements in Trolleys, of which the following is a specification, reference being had therein to the accompanying drawings.

This invention relates to certain new and useful improvements in trolleys adapted particularly for use in connection with overhead trolley-lines; and the primary object of the invention is to provide means for maintaining the trolley in contact with the trolley-wire under ordinary conditions and at least to reduce to a minimum the danger of the trolley accidentally leaving the wire.

Briefly described, the invention comprises a pair of spring-held guard-disks mounted one at each side of the trolley-wheel and each provided with a guard prong or finger projecting upwardly above the rim of the trolley-wheel.

These disks are independently mounted and held by separate springs, whereby they may move independently or in unison. Means is also provided whereby the trolley may be reversed without destroying the function of the disks.

All of the above construction will be hereinafter more specifically described and then particularly pointed out in the appended claim, and in describing the invention in detail reference will be had to the accompanying drawings, forming a part of this specification, and wherein like numerals of reference will be employed for designating like parts throughout the several views, in which—

Figure 1 is a side elevation showing the position of the trolley when in engagement with the trolley-wire, the stem or shank of the harp being broken away. Fig. 2 is a central vertical sectional view of the same. Fig. 3 is a front elevation thereof. Fig. 4 is an edge view of one of the spring-held disks detached, and Fig. 5 is a detail side elevation of the same.

In connection with our invention it is to be

noted that we may take the ordinary trolley-wheel and harp as generally employed and readily apply our improvements thereto, and therefore in the present illustration we have shown the harp 1 of the ordinary form of construction, the wheel axle or shaft 2 being secured therein by means of cotter-pins or keys 3, extending through the upper ends of the harp, which is the usual practice. At each side of the trolley-wheel 4 we mount on the axle or shaft 2 for free rotation thereon disks 5, each provided with an upwardly-extending prong or finger 6, which prongs or fingers form projections or guards to prevent the accidental displacement of the wheel from the trolley-wire. These projections or guards are held normally in the upright position by means of springs 7, one for each disk, these springs at their respective ends being connected to small screw-eyes 8 and 9, carried by the disks and by the harp, respectively. A convenient method of securing these screw-eyes in position has been found to be by tapping a small hole in the disks and in the harp, threading the same, and threading the shank of the screw therein, and we prefer to provide the disks with tap-holes at opposite sides of their peripheries, as by this means it will be observed that in case it should be desired to reverse the trolley it would simply require the changing of the screw-eyes 8 over onto the opposite side of the disk and the operation of the latter would remain the same. The disks on their inner faces are preferably chamfered off to fit neatly the sides of the trolley-wheel, thus allowing the inner faces of the guards 6 at their lower ends to overlie the rim of the trolley-wheel slightly, as shown at 10, so that the trolley-wire as it leaves the wheel engages this face and is prevented from passing over the side of the wheel. As the guards or fingers engage overhead switches or crossovers they are forced rearwardly, the springs 7 expanding, and as soon as the obstacle is passed these springs instantly return the guards to their upright position to prevent the wheel from leaving the wire.

Attention is directed to the fact that the disks are movable independently of one an-

other, so that in event only one of the guards is engaged with an obstruction the disk carrying the other guard will remain in its normal position. This we have found to be a 5 very desirable feature, especially in rounding curves and the like, as should the trolley be so positioned as to throw the wire against one of the guards and perhaps depress the same the other guard remains elevated and in 10 the guarding position. It is also to be noted that the car may back with perfect safety without removing the trolley from the wire, as the disks rotate freely in either direction.

In the practice of the invention it will be 15 observed that various changes may be made in the details of construction without departing from the general spirit of the invention.

Having fully described our invention, what we claim as new, and desire to secure by Letters Patent, is—

In a trolley, the combination with a harp having bifurcated arms, a shaft connecting said arms, and a wheel mounted on said shaft, of a pair of guard-disks mounted on said shaft and between said arms, one at each side 25 of the wheel, a spring connected to each disk and to a point within the bifurcation of the harp, an integral prong or finger carried by each disk and having its outer face in the same vertical plane with said disk, the inner 30 face of said prong or finger slightly overlying said wheel, and means for reversing said trolley, substantially as described.

In testimony whereof we affix our signatures in the presence of two witnesses.

HARRY H. BRYANT.
JOHN B. McGAW.
